INKING MECHANISM

Charles W. Harrold, Shaker Heights, and Clyde G. Horton, Bedford, Ohio, assignors to Harris-Seybold-Potter Company, Cleveland, Ohio, a corporation of Delaware

Original application December 10, 1934, Serial No. 756,794. Divided and this application November 12, 1935, Serial No. 49,366

14 Claims. (Cl. 101—351)

This invention relates to improvements in inking mechanism, and has to do with the mounting of the inker and with throw-off means therefor.

3 One of the principal objects of the invention is the provision of simple and improved inker throw-off mechanism which is adapted for either manual or automatic operation, together with means associated with the throw-off means for 10 exposing the form rollers of the inker for repair or replacement without disturbing any other elements of the inker.

Other objects and features of novelty will appear as we proceed with the description of that 15 embodiment of the invention which, for the purposes of the present application, we have illustrated in the accompanying drawings, in which

Fig. 1 is a side elevational view of an off-set printing press showing inking mechanism embodying the invention.

Fig. 2 is an end elevation of the same with certain parts removed and others broken away in order to more clearly illustrate the invention.

Fig. 3 is a view similar to Fig. 1, showing the 25 form rollers of the inker thrown off.

Fig. 4 is a further fragmental side elevation, showing the principal part of the inker raised to expose the form rollers.

Fig. 5 is a plan view, partly in section, illustrating the pivotally mounted inker frames, on a smaller scale, and

Fig. 6 is a fragmental elevational view showing the free end of the lower inker frame in its raised position.

35 The present case is a division of our copending application Serial No. 756,794, filed December 10, 1934.

The invention is illustrated herein as applied to an off-set press wherein the frame of the press 40 comprises side members 10 and tie rods 11. In the printing couple illustrated there are three parallel shafts 12, 13 and 14 upon which are rotatably mounted a plate cylinder 15, a blanket cylinder 16, and an impression cylinder 17. There 45 is also a delivery cylinder 18 mounted upon a shaft 19.

20 is a power shaft carrying a belt pulley 21 which may be driven from any convenient source of power. On the shaft 20 there is a pinion 22 which meshes with a gear 23 on a short shaft 24 that carries a pinion 25 on its inner end. Pinion 25 meshes with a gear 26 on blanket cylinder 16. Cylinders 15 and 17 are driven from gear 26 through a gear 27 on cylinder 15 and 50 a similar gear, not shown, on cylinder 17.

In the machine illustrated an automatic throw-off is provided for blanket cylinder 16, which causes that cylinder to move in a direction diagonally downward toward the left away from both of cylinders 15 and 17. As more fully disclosed in our aforesaid application, the cylinder 16 rotates upon shaft 13, and shaft 13 is in turn supported in eccentrics that are rotatably mounted in the frame members 10. These eccentrics are keyed to the shaft so that they both 5 turn together and to the same extent. Consequently they may be actuated from one end of the cylinder only. One such eccentric is illustrated at 28 in the drawings. To it is attached a crank 29.

On the end of crank 29 there is mounted a nodule pin 30 which is perforated to receive the end of a short connecting rod 31, the lower end of which is formed with an eye which surrounds a pin 32 mounted in a bell crank lever 33 which 20 is pivoted to the frame at 34. The lever 33 is provided with two adjustable studs 35 and 36 which are adapted to engage with stop blocks 37 and 38 respectively on the frame of the machine, thereby limiting the movement of the lever in 25 either direction.

The right-hand end of lever 33, as viewed in Figs. 1 and 3, is formed with a slot 39 which receives a pin 40 that is mounted in a lever 41 which pivots upon a pin 50 set into the frame 10. 30 The lever 41 is also provided with two forwardly projecting pins 51 and 52. These latter pins are adapted to be engaged on their lower sides by shoulders on the opposite sides of a plunger 53 which carries a roller follower on its lower end. 35 This follower runs upon a cam 54 which is pinned to shaft 19.

Pivotedly connected with the plunger 53 is a trip rod 57 which may be automatically operated in connection with the sheet feeding mechanism of the press, or manually operated. It is shown in Fig. 1 in the normal running position. In order to guide the lower end of plunger 53 and in order to provide pressure to hold the plunger follower against the surface of cam 54, 45 we mount the lower end of the plunger upon a pivot 58 carried by the bifurcated end of a bell crank lever 59 which is pivotally mounted upon the frame at 60. Within the bifurcated extremity of the other end of lever 59 we pivot a rod 61 50 which is slidably mounted in a perforated ear 62 projecting from the frame 10. A coil spring 63 surrounds the rod 61 between the ear 62 and adjusting nuts 64 threadably mounted on the rod. Spring 63 therefore tends to lower pivot pin 58. 55

Now, assuming that the sheet feeding means of the press is provided with an automatic trip mechanism, then when there is an interruption to the feeding of the sheets the rod 57 moves toward the left from the position illustrated in Fig. 1, throwing the plunger 53 against the side of pin 51. As the high spot of cam 54 raises plunger 53 the shoulder on the left of the plunger engages pin 51 and pushes it upward, thereby swinging the lever 41 from the position of Fig. 1 to that of Fig. 3. Lever 33 is thereby swung to the position of Fig. 3, pulling downwardly upon the outer end of crank 29, and imparting a slight clockwise rotation to eccentric 28, which moves the shaft 13 sufficiently to throw cylinder 16 out of contact with cylinders 15 and 17.

The inker includes a lower frame 80, which comprises two independent side members. This frame is pivotally mounted at one end upon a short shaft 81 which is fixed in an upwardly projecting part of the frame 10, and at the other upon a sleeve 82 mounted in the frame surrounding a short shaft 83, to which reference will be made again hereinafter. The two shafts 81 and 83 are, of course, in alignment. This frame 80 has brackets 84, 85 and 86 in which are rotatably mounted form rollers 87, 88 and 89 respectively, which run upon plate cylinder 15 in the normal printing position, as indicated in Fig. 1.

Also pivoted upon shaft 81 and sleeve 82 is a second or upper frame 90, having side members and cross struts. While the pivotal mounting of frames 80 and 90 about a common axis is the preferred construction, it is permissible to mount them upon separate axes, and one of them may be pivotally carried by the other, the latter being pivoted in the main frame of the machine. In frame 90 there may be mounted the remaining elements of the inker, including an ink fountain 91, an ink drum 92, storage rollers 93 and 93', and idler gears 94 and 95. A gear 96 on the inner end of shaft 83 meshes with idler 94 which drives a gear 97 on the shaft of roller 93, while idler 95 takes its driving force from gear 97 and transmits rotation to a gear 98 on the shaft of drum 92 and to a gear 99 on the shaft of roller 93'. In the operative position of the inker, the two storage rollers 93 and 93' transfer ink to the form rollers 87, 88 and 89 which spread it upon the plate cylinder 15.

The forward ends of the two side members of frame 80 are recessed to fit over upwardly projecting portions of the side members of the main frame 10. Within each of these side members are sockets receiving plungers 100 that are pressed upwardly by coil springs 101. The plungers engage the side members of the frame 80 and tend to raise that frame to the extent indicated in Figs. 3, 4 and 6. The forward ends of the side members of frame 90 rest upon the forward ends of frame 80 and hence are influenced by the springs 101 and their plungers 100.

We provide means, however, to pull down the forward ends of frame 90 against the action of springs 101 and to hold both frames in their lowered position, indicated in Fig. 1, this means serving further to raise upper frame 90 to its fully elevated position shown in Fig. 4. The means in question comprises a pair of connecting rods 102 adjustably pivoted to the forward ends of the side members of frame 90. The lower extremities of these connecting rods are curved and are pivotally connected at 103 with cranks 103' carried outside the main frame members 75 by a rock shaft 104. On one end of this shaft

there is pinned a hand crank 105 by means of which the shaft may be turned from one extreme position, illustrated in Fig. 1, through an intermediate position, illustrated in Fig. 3, where the springs 101 are free to act, and to its other extreme position, illustrated in Fig. 4, where the frame 90 is separated entirely from frame 80 and raised high enough to expose form rollers 87, 88 and 89 for removal and replacement. It will be noted that in Fig. 1 the pivot point 103 is over center in one direction, while in Fig. 4 it is over center in the other direction. Hence when either one of these positions has been assumed, the parts tend to remain in that position.

An adjustable screw 106 mounted in one of the connecting rods 102 engages the shaft 104 and limits the downward movement of rods 102 and the clockwise movement of crank 105. An adjustable screw 107 carried by the main frame 10 engages a projection 108 on the crank 105 and limits the upward travel of frame 90, as indicated in Fig. 4.

It is desirable that the form rollers 87, 88 and 89 be lifted out of engagement with cylinder 15 whenever the feed of paper sheets is interrupted, and to this end we provide means for shifting crank 105 from the position of Fig. 1 to that of Fig. 3 whenever the throw-off for blanket cylinder 16 is operated. This means consists of a rod 109 pivoted upon the extremity of pivot pin 32 and resiliently supported from eccentric 28 by a coil spring 110. At its free end this rod is made slightly concave so as to fit upon projection 108 of crank 105. When the tripping mechanism of the press operates to shift rod 57 toward the left from the position of Fig. 1, and the plunger 53 is raised by cam 54, moving levers 41 and 33 to the positions of Fig. 3, rod 109 is carried toward the left and swings lever 105 over dead center, whereupon springs 101 exert pressure acting through plungers 100 to lift the forward extremities of frames 80 and 90, thereby raising the form rollers 87, 88 and 89 sufficiently to clear plate cylinder 15.

On shaft 24 outside of frame 10 there is a sprocket wheel 117 over which runs a chain 118 that extends upwardly and over a sprocket wheel 119 on shaft 83. It is by this means that the inker rollers are driven.

The dampening mechanism, which is indicated diagrammatically in the drawings, comprises a frame 120, a fountain roller 121, a swinging ductor roller 122, a pair of rollers 123 and 124 in contact with the plate on the plate cylinder 15, and an intermediate roller 125. Roller 125 carries a gear which meshes with a gear mounted in frame 10 and indicated at 126, which in turn meshes with a gear 127 on shaft 83. (See Figs. 2 and 5.)

From the foregoing it will be apparent that whenever there is an interruption in the feed of sheets to the press, both of the frames 80 and 90 are automatically raised to prevent further inking of the plate cylinder, and that this is accomplished by swinging the entire ink mechanism upwardly about its pivotal mounting. It will also be apparent that by the manipulation of lever 105 the inking of plate cylinder 15 may be discontinued manually, that is by throwing lever 105 to the position of Fig. 3, and that by continuing the movement of lever 105 to the position of Fig. 4 the upper frame 90 may be raised independently of frame 80 far enough to expose form rollers 87, 88 and 89, permitting their re-

removal if desired, and without disturbing the other parts of the inking mechanism.

Variations from the described structure may be employed. Accordingly we desire it to be understood that the scope of the invention is to be regarded as defined exclusively by the appended claims rather than by the foregoing description or the accompanying illustrations.

Having thus described our invention, we claim:

1. In a machine of the class described, a main frame, an inker comprising two frames each movably mounted on said main frame independently of the other, one of said frames carrying a form roll and the other carrying means continuously engaging said form roll for inking the same, and throw-off means for moving said two frames out of operative position.

2. In a machine of the class described, a main frame, an inker comprising two frames each mounted on the main frame to swing about a horizontal axis, one of said inker frames carrying a form roll and the other carrying means continuously engaging said form roll for inking the same, and throw-off means for moving said two frames simultaneously out of operative position.

3. In a machine of the class described, a main frame, an inker comprising two frames each mounted on the main frame to swing about a horizontal axis, one of said inker frames carrying a form roll and the other carrying inking apparatus adapted to cooperate with said form roll continuously during the normal operation of the inker, throw-off means for moving said two frames simultaneously out of operative position, and means for moving that one of said frames which carries the last named inking apparatus away from operative position to a greater extent than the frame which carries the form roll.

4. In a machine of the class described, a pair of swinging frames pivotally mounted about the same axis, inking apparatus carried partly by one frame and partly by the other, means for holding both of said frames in operative position, spring means tending to shift both frames out of operative position, means for releasing said holding means, and means for moving one of said frames about said axis to increase the angle between the frames and separate that portion of the inking apparatus carried by one frame from the portion carried by the other frame.

5. In a printing press, a printing couple, an inker comprising two frames pivotally mounted to swing about the same axis, a form roll mounted upon one of said frames, a distributing roll mounted on the other frame and adapted to cooperate with said form roll, a throw-off for said printing couple, trip mechanism arranged to operate said throw-off and swing said first-mentioned frame away from operative position, and means for manually swinging one of said frames away from the other frame in order to expose said form roll.

6. In a printing press, an inker comprising a frame pivotally mounted to swing about a horizontal axis, spring means tending to raise the free end of said frame to a limited extent, a lever and link mechanism arranged when in one position to hold down said frame against the action of said spring, when in another position to permit the raising of the frame by said spring means, and when moved to a third position to raise the free end of said frame beyond the elevation resulting from the action of said spring means.

7. In a machine of the class described, an inker comprising an ink fountain, two frames, a form

roller carried by one of said frames, first and second distributing rollers carried by the other of said frames, said first distributing roller being normally in contact with said form roller and with said second distributing roller, said second distributing roller being located between the ink fountain and said first distributing roller for conveying ink from the former to the latter, power operated means controlled by said machine for moving both of said frames away from operative position while maintaining the positions of all three of said rollers relative to each other, and means for separating said form roller from said first distributing roller comprising means for moving one of said frames relative to the other.

8. In a machine of the class described, an inker comprising an ink fountain, two pivotally mounted frames, a form roller carried by one of said frames, first and second ink distributing rollers carried by the other of said frames, said first distributing roller being normally in contact with said form roller, said second distributing roller being located between the ink fountain and said first distributing roller for conveying ink from the former to the latter, means for swinging said two frames about the axis of one of them out of operative position while maintaining the positions of the rollers carried thereby in the same relation relative to each other, and means for swinging one of said frames about its pivot relative to the other frame to separate said form roller from said first distributing roller.

9. In a machine of the class described, an inker comprising first and second pivotally mounted frames adapted to swing about a common axis, a form roller carried by said first frame, an inking roller normally in contact with said form roller and carried by said second frame, means for swinging one of said frames about its axis relative to the other frame for separating said rollers, and a gear for driving said last mentioned roller mounted to turn on the common axis of said frames.

10. In a machine of the class described, an inker comprising first and second pivotally mounted frames, a form roller carried by said first frame, a plurality of positively driven elements for inking said form roller carried by said second frame, means for swinging both of said frames about a common axis out of operative position, means for swinging one of said frames about its axis relative to the other frame, and gearing for said positively driven elements including a gear mounted to turn on the common axis of said frames.

11. In a machine of the class described, an inker comprising first and second pivotally mounted frames, a form roller carried by said first frame, an ink fountain and associated elements carried by said second frame, throw-off means for moving said two frames simultaneously about a common axis out of operative position, and a gear for driving said ink fountain and associated elements mounted to turn on the common axis of said frames.

12. In a machine of the class described, a main frame, an inker comprising two frames each movably mounted with respect to the other, inking apparatus carried partly by one frame and partly by the other, operative connections acting on one of said frames for moving both frames into operative position and holding them there under pressure, and means acting on the other of said frames for moving both frames out of operating position.

13. In a machine of the class described, a main

frame, an inker comprising two frames each movably mounted with respect to the other, inking apparatus carried partly by one frame and partly by the other, operative connections acting on one of said inker frames for moving both inker frames toward said main frame into operative position and holding them there under pressure, and resilient means acting on the other of said inker frames tending to oppose said movement and 10 when freed from the restraint of said first named means serving to move both frames out of operative position.

14. In a machine of the class described, a main frame, an inker comprising two frames each movably mounted with respect to the other, the first 15

of said inker frames carrying a plurality of form rolls and the second carrying mechanism for inking said form rolls, said first inker frame being intermediate the second inker frame and the main frame, each of said first and second inker frames being mounted to permit it to follow movement of the other frame, connections between the main frame and said first inker frame for moving the latter out of operative position, and connections between the main frame and said second inker frame for moving the latter into operative position. 5 10

CHARLES W. HARROLD.
